UNITED STATES PATENT OFFICE.

LIBANUS M. TODD, OF ROCHESTER, NEW YORK.

SHELTER.

Application filed February 12, 1923. Serial No. 618,475.

To all whom it may concern:

Be it known that I, LIBANUS M. TODD, a citizen of the United States, residing at Rochester, in the county of Monroe and 5 State of New York, have invented certain new and useful Improvements in Shelters; and I do hereby declare the following to be a full, clear, and exact description of the same, reference being had to the accompanying drawings, forming a part of this specification, and to the reference numerals marked thereon.

This invention relates to shelters and more particularly to those having the general character of marquees, pergolas, and the like, one object of the invention being to provide a simple, practical and efficient structure of this character having various features of utility and convenience and capable of being made and erected at a comparatively low cost.

Another object of the invention is to provide a structure of the above character having features rendering it particularly suitable also for use at the tee stations of golf courses and having combined therewith means for collecting and retaining rain fall to supply water for the use of the players. To these and other ends the invention resides in certain improvements and combinations of parts all as will be hereinafter more fully described, the novel features being pointed out in the claims at the end of the specification.

35 In the drawings:

Figure 1 is a side elevation partly in section showing a form of shelter embodying the present invention.

Figure 2 is a top plan view of the same.

40 Figure 3 is an enlarged fragmentary detail section on the line 3^a—3^a of Figure 2.

Figure 4 is an enlarged detail section on the line 4^a—4^a of Figure 1.

45 Figure 5 is a fragmentary elevation of parts shown in Figure 4 as viewed from the right.

Figure 6 is a sectional view of parts shown in Figure 4 in a different position.

Figure 7 is a sectional view on the line 7^a—7^a of Figure 1 and 50

Figure 8 is an enlarged detail view of an over flow connection shown in Figure 1.

Similar reference numerals throughout the several views indicate the same parts.

The embodiment of the invention at present preferred and selected for disclosure herein by way of illustration of the principles involved, comprises a central supporting column 10 which may be advantageously constructed of cast iron. This column is 60 of a substantial character as shown and is formed in the present instance with a foot portion 11 adapted to be mounted in a concrete block 12 extending to a substantial depth under ground to afford a rigid support. When constructed as a casting, the column may be readily fluted and otherwise ornamented as taste may dictate. The present embodiment of the invention shows a 65 form thereof particularly adapted for use 70 on a golf course and in this embodiment the column is preferably of hollow construction above the ground having an interior bore or chamber 13, for purposes presently to appear. 75

The top or roof of the shelter is preferably rigid and supported on the column at a point spaced below the top of the latter for which purpose the column is constructed with a shoulder in the form of a laterally extending flange 14. The top 15 is in the present instance constructed of sheet metal and is of circular shape with an opening at its center, through which the upper end of the column is passed. The edges 80 of this opening are seated upon the shoulder or flange 14 and secured thereto as by means of bolts or rivets 16. At its periphery top 15 is rolled upwardly and outwardly to provide a flange 17 to which is secured, 85 in any suitable manner, flange means in the form of a sheet metal strip or hoop 18 extending above and below the top and preferably having a slightly areuate shape as shown. The upper and lower margins 90 of this flange 18 are preferably rolled upon 95

themselves as at 19 to strengthen and finish them off, and this flange means serves not only to stiffen and re-inforce the top proper but also to support the periphery of the latter on the column, as well as to carry the side curtain means hereafter described.

The periphery of the top is supported from the column by means of a plurality of stay rods 20 comprising headed sleeves 21, Figure 4, passed through openings in the flanges 17 and 18. These sleeves have threaded bores into which the rods 20 are adjustably screwed, the rods extending thence radially inwardly and upwardly toward the upper end of the column 21 which projects above the top. This end of the column is provided, as best shown in Figure 3, with a cap 22 of generally hemispherical shape having interior lugs 23 formed with seats 24 resting upon the upper end of the column. The cap is constructed around the inner side of its lower edge with a series of spaced vertical ribs 25 between which the cap is provided with openings through which the stay rods 20 are passed. Nuts 26 secure the ends of the rods and are prevented from turning by the ribs 25. Projecting upwardly from the cap is a standard 27 carrying, if desired, a suitable ornamental device such for example, as the arrow wind vane 28.

Curtain means are supported at the periphery of the top for enclosing the space beneath the latter and are preferably in the form of vertically extending sections of suitable width so that either the whole space or any desired side thereof may be closed in. This curtain means is preferably suspended from the inner side of the flange 18 below the top, to which end there are secured to the flange a series of brackets 30, Figures 4 and 5. The curtain sections are each looped over a rod 31 having a length substantially equal to the width of the section and these rods with the curtains attached are inserted between the brackets 30 and the flange 18 and supported thereby in a simple and detachable manner. The sections overlap each other slightly as shown, and are provided with means, such as the buttons 32, for securing adjacent vertical section edges together. The sections are also provided adjacent their lower ends with means for anchoring the same to the ground comprising hooks 33 carried by the curtains for detachable engagement with rings 34 secured at the surface of the ground by any suitable anchoring means such as shown at 35. Means are also provided for retaining the curtain sections together or individually in raised relation under the top when not in use, comprising a series of bracket arms 36, Figures 4 and 6, secured at one end to the brackets 30 and curved as shown to receive and securely retain the curtain rolled upwardly

from its lower end. The bracket arms 36, which may be of resilient metal, extend sufficiently close to the top to require some compression of the curtain roll in moving the latter to and from the compact position shown, thereby preventing the curtain, when once so disposed, from falling or being blown down and the curtains when thus raised are effectively protected from the weather.

To afford some protection when the curtain sections are not required and to finish off and embellish the structure, there is provided a lambrequin 37 extending continuously around the periphery of the top outside the curtains as shown, and looped at its upper edge about rod means 38, Figures 4 and 5, detachably secured to the inner side of flange 18 by means of brackets 39 bolted or otherwise secured to the flange, as described in connection with the curtain sections.

As already stated, the present embodiment of the invention is particularly adapted for use at the tees of golf courses where a supply of water is desirable and to this end the top is made watertight and arranged to collect and retain the rain water falling thereon, being preferably dished downwardly from its periphery toward the column as shown. The latter above the top has openings formed therein as shown at 40 for the discharge of collected water into the column interior which with the concave top affords a reservoir of substantial capacity. Suitable dispensing means are conveniently located adjacent the base of the column, comprising in the present instance a spigot 41 tapped into the column in communication with its interior. By this means a supply of water is usually insured for moistening the sand for making tees, for washing purposes and the like. An overflow connection is also provided to discharge surplus water when the top and column have been sufficiently supplied; such means comprises in the present instance, a pipe 42 extending vertically inside the column and having at its upper end a threaded extension 43 carried laterally through one of the openings 40 in the column above the top. Extension 43 has threadedly engaged therewith an angular pipe section 44 which may be adjusted or rotated on the extension to adjust the elevation of its end above the top and thus regulate the level at which the collected water drains through pipe 42. The latter is carried through the base of the column as at 45 into a suitable discharge trough 46. The bore 13 of the column is preferably tapered inwardly somewhat at its bottom as shown to force ice upwardly and overcome its expansive action in case of freezing in winter.

It is apparent from the above description

that the invention provides an exceedingly effective and convenient shelter adapted for a wide variety of uses such, for example as affording protection for one or more persons at tees of golf courses and other recreation spots or points of observation, serving as a pleasure house for the lawn or garden, protecting children's sand boxes, and the like. In bad weather with the curtain sections lowered and secured to the ground, effective protection is obtained. In fair weather the curtain sections may be easily detached from their ground anchorage, rolled upwardly from the bottom and placed on the supporting brackets 36 where they are not only fully protected from the weather but are also neatly and compactly disposed out of view behind the lambrequin 37. If desired, such a number only of the sections may be employed as required to afford protection at one side of the shelter against rain, wind or sun. Or such curtain sections only may be raised on any side of the shelter as to afford outlook in any desired direction. The shelter is particularly advantageous for golf courses by reason of the means described for collecting and dispensing water, in combination with the above features. Column 10 may be used as a support for various equipment such as the clock shown in Figure 1. In addition to the features of utility described, the construction is simple, rugged and economical in character, as well as ornamental and pleasing in appearance.

I claim as my invention:

1. A shelter comprising a central supporting column, a rigid top carried thereby and projecting laterally therefrom, curtain sections depending from the periphery of the top and adapted to either extend adjacent the ground or be rolled upwardly out of use, and supporting means on the under side of said top for supporting the rolled up portions of the curtain sections.

2. In a shelter, a central supporting column having a shoulder spaced below its upper end, a rigid top supported centrally on said shoulder and projecting laterally from the column, stay rods connecting the upper end of the column and the periphery of said top, curtains suspended from the periphery of said top and adapted to either depend adjacent the ground or be raised out of use, and means for retaining said curtains in either of said positions.

3. In a shelter, a central supporting column, a top supported on and projecting laterally from the column below the upper end thereof and comprising at the periphery of the top a flange projecting above and below the same side curtains depending from said flange below said top, and stay rods connecting said flange above the top with the upper end of said column.

4. In a shelter, supporting means, a top

carried thereby arranged to collect and retain rain water, means for dispensing said water for use, and side curtains suspended from the periphery of said top to enclose the space thereunder. 70

5. In a shelter, a central supporting column, a top carried thereby and dished downwardly toward the column to collect and retain water falling thereon, means for dispensing said water for use, and side curtains suspended from the top to enclose the space thereunder. 75

6. In a shelter, a hollow, supporting column, a top supported centrally thereby and dished downwardly toward the column to collect water falling thereon, said column being formed to provide communication between the upper side of the top at its lower portion and the interior of the column for admitting collected water to the latter, 80 means adjacent the base of the column for dispensing water therefrom for use, and curtains carried by the top to enclose the space thereunder. 85

7. In a shelter, a hollow supporting column having a shoulder spaced below its upper end, a top supported centrally on said shoulder and arranged to collect water falling thereon and discharge the same through an opening into the column interior, stay 90 rods connecting the periphery of the top with the upper end of the column, means adjacent the base of the column for dispensing the water for use, curtains carried by the top to enclose the space thereunder, and 100 means for securing said curtains in raised or lowered positions.

8. In a shelter, a hollow supporting column having a shoulder spaced below its upper end, a sheet metal top supported centrally on said shoulder and projecting laterally from the column, said top being dished downwardly toward the column to collect and discharge rainfall thereinto, means adjacent the bottom of the column for dispensing water therefrom, a flange about the periphery of said top extending above and below the same, stay rods connecting said flange with the upper end of said column, and curtain means in separable sections depending from said flange for wholly or partially enclosing the space beneath said top. 110

9. In a shelter, a supporting column having a shoulder spaced below its upper end, a sheet metal top supported on said shoulder 120 and projecting laterally from the column, said top being arranged to collect and retain water falling thereon, means for dispensing the water for use, an overflow connection for discharging surplus water collected by said top, curtains depending in separable sections from the top to wholly or partially enclose the space beneath the latter, and a lambrequin depending from said top outside said curtains. 125

10. In a shelter, a supporting column, a substantially circular top supported centrally by said column below the upper end of the latter, said top being provided at its periphery with flange means extending above and below the same, stay rods connecting said flange with the upper end of the column, curtains depending in sections from said flange, to enclose the space beneath said
- 10 top and provided with means for securing the sides of adjacent sections together and the ends thereof to the ground, means for retaining one or more of said sections in raised relation when not in use, and a lambrequin carried by said flange outside said 15 curtains.

LIBANUS M. TODD.
